SASH CONSTRUCTION

Julius C. Neuendorf, Detroit, Mich.

Application March 30, 1937, Serial No. 133,799

2 Claims. (Cl. 20—56.5)

This invention relates to sash construction and the object of the invention is to provide a sash which to all appearances is composed of divided lights but which actually consists of clear sheets of glass mounted in spaced relation in the sash and provided with dividing muntin bars between the glass panes to give the appearance of divided lights.

One of the particular objects of the invention is to provide a sash having two panes of glass mounted in spaced relation and which may be readily washed over the entire surface without the troublesome cleaning in the corners necessitated in a divided sash while the sash, at the same time, has the appearance of a divided sash without any of its drawbacks.

Another object of the invention is to produce a sash having the appearance of a divided sash but which does not require the fitting of small panes of glass between the muntin bars.

A further object of the invention is to provide a double glazed window consisting of a pair of glass panes sealed in rubber and positioned against opposite sides of assembled muntin bars to provide a sash having air spaces for insulation with the panes of glass sealed at the edges to the sash.

A further object of the invention is to provide muntin bars which may be assembled and enclosed between the two panes of glass to properly space and support the panes of glass within the edges and providing in combination with the panes of glass, a unitary structure having a series of small dead air pockets.

These objects and the several novel features of the invention are hereinafter more fully described and claimed and the preferred form of construction by which these objects are attained is shown in the accompanying drawing in which—

Fig. 1 is an elevation of a sash embodying my invention.

Fig. 2 is an enlarged section taken on line 2—2 of Fig. 1.

Fig. 3 is an elevation of the assembled muntin bars to be positioned between the glass panes.

Fig. 4 is an enlarged section taken on line 4—4 of Fig. 3.

Fig. 5 is a view of one of the muntin bars.

Fig. 6 is a perspective view of the other muntin bar with which the muntin bar end shown in Fig. 5 is to be assembled.

The sash is shown in section at the left of Fig. 2 and comprises a sash member 1 having an inwardly extending rib 2 between the sides and having shoulders 3 and 4 formed on opposite sides of

the rib 2. A rubber channel 5 is fitted about the edge of each pane of glass 6 and these panes with the rubber channels therein are positioned on opposite sides of the central rib 2 and on the shoulders 3 and 4. Slots 7 are cut into the sash 5 to receive the edges of the securing spring metal strips 8 and these strips are turned outwardly and are return bent to provide a spring flange 9 which engages and presses the glass panes against the central rib 2. As the flanges 9 are of spring 10 metal, they firmly hold the panes in place and compress the rubber channel portions against the rib 2 and nails 10 may be driven through the sash and member 8 as shown in Fig. 2 to secure the spring metal strips in place in their slots. The 15 spring metal strip construction is covered more particularly in my co-pending application, Serial No. 109,848, for Metal sash strips, filed November 9, 1936. If desired, however, putty may be used in place of the spring metal strips 8 to secure the 20 glass panes in place in the sash.

A series of muntin bars are positioned between the spaced glass panes 6. These muntin bars are different than the ordinary muntin bars in that they are not provided with shoulders against 25 which the small panes of glass are usually fitted. In fact, the muntin bars are merely imitation muntin bars and are not strictly muntin bars in the true sense of the word in that they support no small glass panes. The cross section of one 30 of the muntin bars is shown in Fig. 6 and this muntin bar 11 is provided with flat surfaces 12 and 14 against which the glass panes 6 may rest. The muntin bars are assembled by forming the end of one muntin bar as shown in Fig. 5 with a 35 flat groove 15 to receive the edge 16 of the other muntin bar and this groove 15 is provided with curved faces 17 to fit the curved faces 18 of the other muntin bar. The muntin bar shown in Fig. 5 is provided with extending ends 19 adapted 40 to fit into notches 20 provided in the ribs 12 and 14 of the other muntin bar as will be understood from Figs. 4, 5 and 6. These ends 19 extend only half way through the rib 12 as will be understood from Figs. 3 and 4 and the muntin bars are assembled by providing two longitudinal bars 11 and a series of transverse muntin bars 21 which are formed with the notched ends shown in Fig. 5. These muntin bars are assembled and glued together as shown in Figs. 3 and 4 and are then 50 ready for installation in assembling the sash.

One glass panel is first secured in position and then the assembled muntin bar shown in Fig. 3 is placed within the plane of the rib 2 which extends on the four sides of the sash and then the 55

other glass pane is assembled against the muntin bars. By this arrangement, the assembled muntin bars rest against the ribs 2 of the sash members and the glass panels contact the ribs 12 and 14 of the muntin bars.

Thus, the assembled muntin bars space the glass panels apart and support the same and also divide the sash into a series of dead air pockets which provides insulation from heat and cold 10 and is especially valuable for use with air conditioned buildings.

One of the principal objections to divided sash which are so popular in colonial type houses is due to the fact that it is a tiresome and careful 15 job to wash the usual small panes of glass provided by the divided sash. With my construction, however, two smooth large glass panes are provided which may be very easily washed in a small part of the time required to wash the 20 usual divided sash glasses. Also, this smooth surface is provided on both the exterior and the interior and it is only these surfaces that need to be washed. My construction also overcomes the expense and labor of glazing the large number 25 of small lights required in the usual divided sash of this nature. At the same time, the appearance of the sash is that of a divided sash both from the interior and the exterior of the building and the fact that the glass panes are 30 on the outside of the muntin bars cannot be detected except upon very close inspection. By this construction, the muntin bars strengthen and support the glass panes and as the muntin bars act as reinforcements for both panes it 35 will support the glass against considerable pressure and forms a rigid unit which will resist breakage by wind storms, tornadoes, etc. Also, the number of small dead air pockets formed by the muntin bars gives greater insulating value in 40 that the air has no space in which to circulate and transfer heat or cold from one pane to the other. By removal of one pane, the muntin bars may be readily lifted out to allow cleaning of the insides of the glass panes should it ever become 45 necessary.

While I have described the muntin bars as be-

ing made of wood, they may also be made of hollow metal, extruded metal or metal tubing of the desired shape and of other materials practical for this use. In fact, any material may be used which may be enclosed between the glass panes 5 and will have the appearance of muntin bars.

From the foregoing description it becomes evident that the device is very simple and efficient in operation, will have the appearance of a divided sash without its disadvantages, provides an 10 air sealed insulating sash and provides a device which accomplishes the objects described.

Having thus fully described my invention, its utility and mode of operation, what I claim and desire to secure by Letters Patent of the United 15 States is—

1. In a sash construction, a rectangular sash having an inwardly extending rib on each side, a pair of glass panes for the sash, a rubber channel extending about the edge of each glass pane, the 20 glass panes being positioned on opposite sides of the ribs with the rubber channels engaging the ribs, a series of spring flanges secured to each side of the sash and pressing the glass panes toward each other to provide a sealed air space 25 between the glass panes and a series of muntin bars assembled together and positioned between the glass panes, the muntin bars dividing the sealed air space between the glass panes into a series of air pockets.

2. In a sash construction, a rectangular sash having an inwardly extending rib on each side, a pair of glass panes for the sash, a gasket extending about the edge of each glass pane, the 30 glass panes being positioned on opposite sides of the ribs with the gaskets engaging the ribs, a series of spring flanges secured to each side of each sash and pressing the glass panes toward each other to provide a sealed air space between the glass panes and a series of muntin bars assembled together and positioned between the 35 glass panes, the muntin bars dividing the sealed air space between the glass panes into a series of air pockets.
